UNITED STATES PATENT OFFICE.

JOHN L. GOLDSTEIN, OF PHILADELPHIA, PENNSYLVANIA.

CHILD'S CARRIAGE.

968,763.

Specification of Letters Patent. Patented Aug. 30, 1910.

Application filed March 25, 1910. Serial No. 551,423.

To all whom it may concern:

Be it known that I, JOHN L. GOLDSTEIN, a citizen of the United States, residing at Philadelphia, in the county of Philadelphia and State of Pennsylvania, have invented 5 certain new and useful Improvements in Children's Carriages, of which the following is a specification.

My invention relates to improvements in 10 children's carriages, the object of the invention being to provide an improved mounting at both ends of the carriage spring for the handle, so that the handle may be shifted from end to end of the carriage 15 as desired. This is especially desirable, as it enables the carriage to be propelled in either direction, so that the child may be riding either forward or backward, and in windy weather may be fully protected by the ordinary carriage cover or top.

With these and other objects in view, the invention consists in certain novel features of construction, and combinations and arrangements of parts as will be more fully 25 hereinafter described and pointed out in the claim.

In the accompanying drawings: Figure 1, is a view in side elevation illustrating my improvements. Fig. 2, is an end view. Fig. 30 3, is an enlarged view in longitudinal section, illustrating the handle attaching mechanism. Fig. 4, is a view in elevation of Fig. 3. Fig. 5, is an enlarged perspective view of one of the members of the handle. Fig. 6, 35 is a perspective view of one of the cam levers, and Fig. 7, is a perspective view of one of the straps.

1, represents the body of an ordinary carriage, which is supported on springs 2, and 40 the latter secured upon axles 3, mounted in wheels 4.

Body 1, is provided with the ordinary cover 5, and may be connected with the springs 2 in various ways, one ordinary way 45 in common use being illustrated. As my invention is in nowise limited to the particular construction of the carriage, it is not necessary to further go into the details of the carriage structure.

50 The parallel springs 2, extend upward at their ends, as shown, and each of these upwardly extending ends of each spring, is provided with a construction exactly alike, and the description hereinafter of one will

apply alike to all. On the spring 2, metal straps 6, and 7, are secured, and spaced apart, and are adapted to receive the flattened end portion 8, of one of the carriage handle members 9, said carriage handle members 9, connected by a handle bar 10. 55

The lower strap 7, is provided with an opening 11, and outwardly projecting perforated ears 12, between which a cam lever 13 is pivotally supported on a pin 14, and is provided with a handle 15 to operate the 60 same, said handle being preferably of curved form, as shown.

The flattened member 8, is provided with a lug 16, to engage the upper strap 6, and limit the downward movement of the handles, and said flattened member is also provided with a curved recess 17, into which the cam lever tightly fits, when the lever is swung to its lowest position, illustrated in Figs. 3, and 4, to securely lock the handles 75 to the springs.

When it is desired to remove the handles, the levers are swung upwardly to bring their cam portions out of the recesses 17, when the handles can be readily removed. 80

The levers 13, normally hang in a position shown in Fig. 1, and when the flattened portions 8, are inserted through the straps 6, and 7, they will cause the levers to swing upwardly, and in a good many instances they will fall to locked position without manual manipulation. The handles may therefore be readily moved from one end of the carriage to the other, and may be secured locked at either end. 85

Various slight changes might be made in the general form and arrangement of parts described without departing from my invention, and hence I do not limit myself to the precise details set forth, but consider myself at liberty to make such changes and alterations as fairly fall within the spirit and scope of the appended claim. 90

Having thus described my invention, what I claim as new and desire to secure by Letters Patent is:

In a device of the character described, the combination with a body, springs having upwardly projecting ends supporting the body, axles supporting the springs, and wheels supporting the axles, of straps secured to the upwardly projecting ends of the springs at both ends of the carriage, cam

levers supported in the lower straps and
movable through openings in the latter,
handles having flattened members to be po-
sitioned in said straps, and having recesses
5 to receive said cam levers, and lugs on said
flattened members to engage the upper
straps, substantially as described.

In testimony whereof I have signed my
name to this specification in the presence of
two subscribing witnesses.

JOHN L. GOLDSTEIN.
